UNITED STATES PATENT OFFICE.

AUGUSTE A. GOUBERT, OF NEW YORK, N. Y., ASSIGNOR TO THE F. O. MATTHIESSEN AND WIECHERS SUGAR REFINING COMPANY, OF JERSEY CITY, N. J.

IMPROVEMENT IN APPARATUS FOR LIQUORING SUGAR IN CENTRIFUGAL MACHINES.

Specification forming part of Letters Patent No. 221,893, dated November 18, 1879; application filed September 2, 1879.

To all whom it may concern:

Be it known that I, AUGUSTE A. GOUBERT, of the city and State of New York, have invented certain Improvements in Apparatus for Liquoring Sugar in the Centrifugal Machine, of which the following is a specification.

My improvements relate to the class of devices for imparting simultaneous radial movements to the boxes used to conduct white liquor discharged from the central chamber or reservoir of a centrifugal machine into the several sugar-molds with which the boxes, by one motion, are respectively brought into close contact for the purpose of preventing the escape of the white liquor otherwise than through the sugar contained in the molds, and from which the boxes are, by the opposite motion, withdrawn for the purpose of freeing the molds, so that they can be moved from the machine when the liquoring operation is completed; and my invention consists in the combination of the boxes with a diametrically or vertically expansible chamber filled with a fluid and provided with a movable plunger so organized that it may be forced into the chamber for the purpose of causing the expansion of the elastic parts of the chamber, or withdrawn therefrom for the purpose of causing the retraction of the elastic parts of the chamber.

The accompanying drawings, illustrating a centrifugal machine containing my invention, are as follows: Figure 1 is a central vertical section of the machine, showing the boxes thrust outward against the molds by the depression of the plunger in the expansible chamber. Fig. 2 is a top view, partly in section, and Fig. 3 is a central vertical section, showing the boxes withdrawn from contact with the molds, owing to the elevation of the plunger and the reduction in the diameter of the expansible chamber.

The drawings represent the usual basket A of a centrifugal machine mounted upon a vertical spindle, B, and containing a series of concentrically-placed sugar-molds, C, seated in the usual manner between guide walls or pillars e, permanently affixed to the basket.

The machine is provided with the usual central reservoir, D, having the spouts d, by which its contents are discharged into the usual liquoring-boxes E. These boxes are closed at the back or inner side, and are, respectively, affixed to the elastic or flexible shields f, which close the openings in the periphery of the expansible chamber F. These shields may be made of rubber fabric, leather, or any flexible material which is water-tight, and they are connected by water-tight joints with the metallic wall of the chamber F.

The range of radial movement required for the boxes is very small, and their connection, respectively, with the shields f serves to hold them in proper radial alignment with the molds.

The metallic top F' of the chamber F is centrally perforated to admit the tubular plunger G, and is provided with a flanged packing, F², and cap F³ for the purpose of packing the joint with the tubular plunger G. The interior of the hollow plunger G is provided with the female screw-thread g, which engages a male screw-thread on the upper portion, g', of the spindle. The upper end of the plunger G may be provided with a crank, or may be made polygonal for the application of a wrench, by which means it may be turned either to force it down into the chamber F or withdraw it therefrom.

The chamber F is filled with water or other fluid, so that when the plunger is forced down into the chamber the displacement of the contained fluid will effect the expansion of the elastic shields and consequent thrusting of the boxes radially outward against the molds.

By the reverse movement of the plunger G the previously-displaced fluid re-enters the chamber F, and the elastic shields are drawn inward by atmospheric pressure, withdrawing the boxes from the molds, so that the latter can be removed from the basket of the machine.

I claim as my invention in centrifugal liquoring apparatus—

1. A series of movable boxes concentrically arranged in the basket of a centrifugal ma-

chine, in combination with an expandible chamber, with the elastic portion of the side walls of which such boxes are connected, as and for the purposes set forth.

2. A central chamber in the basket of a centrifugal machine, having portions of its side walls, with which a series of movable boxes are connected, composed of an elastic

or flexible material, in combination with a movable plunger for effecting the displacement of a fluid contained within the central chamber, as and for the purpose set forth.

AUG. A. GOUBERT.
